MORTIMER C. ROSENFIELD, OF CLEVELAND, OHIO.

FLOOR OR CEILING PLATE.

1,209,037.

Specification of Letters Patent. Patented Dec. 19, 1916.

Application filed May 2, 1914. Serial No. 835,789.

To all whom it may concern:

Be it known that I, MORTIMER C. ROSENFIELD, a citizen of the United States, residing at Cleveland, in the county of Cuyahoga and State of Ohio, have invented a certain new and useful Improvement in Floor or Ceiling Plates, of which the following is a full, clear, and exact description, reference being had to the accompanying drawings.

10 This invention relates to what are commonly known as floor or ceiling plates for application to pipes where the pipes pass through the floors, ceilings, walls or other parts of buildings, for covering and sealing the holes through which the pipes pass.

20 The objects of the invention are to provide a device of this nature which is attractive in appearance; simple of manufacture; economical of production; and which is extremely convenient of application to a pipe.

25 With the above objects in view I provide a construction set forth in the annexed claims and illustrated in the accompanying drawing which forms a part of this application, wherein—

30 Figure 1 is a section through a pipe which has one of my improved plates applied thereto; Fig. 2 is a section through the pipe showing the side of the plate opposite to that shown in Fig. 1, or the side which is adjacent the floor or other part of the building through which the pipe passes; Fig. 3 is a transverse section on the line 3—3 of Fig. 1, 35 the same showing the plate as applied to a vertical pipe and resting upon the floor; Figs. 4 and 5 are sections taken on the lines 4—4 and 5—5, respectively, of Fig. 1; and Fig. 6 illustrates a modified and simplified 40 form of the plate.

The form of plate illustrated in Figs. 1 to 5 inclusive, and which will be designated, generally, by A, comprises two semi-annual members 1 and 2. Projecting from one 45 end of the member 1 is a semi-circular ear 3, and the opposite end of the same member is provided with a lug or extension 4. It will be stated here that I prefer to make my improved plate of sheet-metal stampings;

and in the formation of the member 1, the 50 metal adjacent the lug or extension 4 is depressed a depth equal to the thickness of the metal. The end of the lug or extension 4, as will be seen most clearly from Fig. 4, is turned downwardly to form an inclined end 55 for the lug; and at about its center, the depressed portion 5 is provided with a slot or aperture 6. Upon referring to Fig. 3, it will be seen that the member 1 has its outer edge turned over at right angles to its 60 body portion to produce a flange or skirt 7, the edge of which is adapted to contact with the surface through which the pipe B extends; and at its inner edge, the member 1 is provided with a bead 8 which renders the 65 plate stiff and substantial, as well as attractive in appearance.

The member 2 is very similar to the member 1, the same having a skirt or flange 10 which extends along its outer edge, and a 70 bead 11 along its inner edge. One end of the member 2 has a semi-circular extension 12, and pivoted to this extension, by the rivet 13, is the extension 3 of the member 1, said extensions being pivoted on a center which 75 is substantially concentric to the curved edges of both. The portion of the member 2 which is overlaid by the projection 3, and adjacent part of member 1, is depressed a depth corresponding to the thickness of 80 said projection or member. Pivoted together in this manner, the members 1 and 2 may be separated as indicated by the dot-and-dash line position of the member 2 in Fig. 1. To permit of this movement, it will 85 be observed that the end of the flange or skirt 10 of the member 2, adjacent the pivoted end of the member, is pressed inwardly as shown at 15 in order that it may clear the end of the flange or skirt 7 of the member 1 90 when the members are swung to open position.

Projecting from the end of the member 2, opposite its pivoted end, is a semi-circular extension 16 that is adapted to be received by 95 the depressed portion 5 of the member 1. At about its center the extension 16 is provided with a depending tongue 17 which extends

from the body portion of the member 2 and is turned downwardly at substantially right angles thereto as shown clearly in Fig. 4. This tongue is arranged to be received by 5 the aperture 6 in the end of the member 1.

Assuming that the parts have been separated for application to a pipe, the plate is placed around the pipe and the parts are 10 pressed together, the tongue 17 engaging and riding up the inclined end of the lug 4 of the member 1 and across the upper surface thereof until it is brought into register with the aperture 6, when, through the resiliency of the metal, it is caused to snap 15 into said aperture.

For securing the plate to the pipe B, I provide a set screw 18 which is threaded through the flange or skirt 10 of the member 2 and which has its inner and smooth end 20 19 guided through an aperture 20 in the ear 21 that depends from the inner edge of the bead 11, and is in radial alinement with the threaded aperture in the flange or skirt 10 through which the screw 18 operates. In 25 this way, the inner end of the screw is very effectively guided and held in place. While I have shown but one of such screws, and have shown it as carried by the member 2, it is obvious that the same might be as ef- 30 fectively carried by the member 1, or that each member might be provided with such a securing means, if desired.

From the foregoing description it will be seen that my invention provides a very convenient floor or ceiling plate, and that the 35 same is very attractive in appearance.

The form of ring shown in Fig. 6 consists of an annulus which is the same, in cross section, as either of the members 1 or 2 of 40 the previous form. This form of plate is for application to a pipe when the same is being installed, and is adapted to be slipped over the end of the pipe and brought into contact with the surface through which the 45 pipe passes. The plate is designated A' and is held in place upon the pipe by the set screw 22 that is threaded through the peripheral skirt or flange 23 and has its smooth, inner end 24 guided by the ear 25.

Having thus described my invention, what I claim is:—

1. A device of the character set forth comprising an annulus having a peripheral flange which extends at right angles from its 55 body portion and a bead which rises from its body portion adjacent its inner edge, the peripheral flange having an opening, a perforated ear which extends from the inner edge of the bead and is in a plane substantially parallel to the plane of the aforesaid flange, and a set screw which is threaded through the opening in the flange and has its inner end guided through the perforation of the aforesaid ear.

2. A device of the character set forth comprising an annulus having a peripheral flange which extends at right angles from its body portion and a bead which rises from its body portion adjacent its inner edge, the peripheral flange having a threaded opening, a perforated ear which extends from the inner edge of the bead and is in a plane substantially parallel to the plane of the aforesaid flange and in radial alinement with the opening thereof, and a set screw 75 which is threaded through the opening in the flange and has a smooth inner end guided through the perforation of the aforesaid ear.

3. A device of the character set forth comprising a pair of substantially semi-annular sheet metal opposed members each of which is provided with a projection which extends from one of its ends, the projections of the two members overlapping, pivotal means 85 connecting said projections, the ends of the members opposite their pivoted ends being provided with overlying extensions, one of said extensions having an aperture and the other a projection which is adapted to be 90 received by said aperture, the portion of one of the members, which is overlaid by a portion of the opposite member, being depressed a depth equal to the thickness of the metal, one of the members having a flange which 95 is provided with a threaded opening and which extends at right angles from its body portion at its outer edge, an ear which depends from the inner edge thereof, said ear having an aperture, and a screw threaded 100 through the opening of the aforesaid flange and having its inner end guided by the aperture of said ear.

4. A device of the character set forth comprising a pair of substantially semi-annular 105 opposed sheet metal members each of which has a projection extending from one of its ends, means pivotally connecting the projections of the members, the ends of the members opposite their pivoted ends having 110 overlying projections, one of which is provided with a tongue, and the other an aperture for the reception of said tongue, the extension having the aperture being inclined 115 downwardly therefrom toward the opposed member, each member having a flange which extends from its outer edge at right angles to its body portion and a bead which rises from the body portion of the member along its inner edge, a perforated ear depending 120 from the inner edge of the bead of one of the members, the flange of the last mentioned member having a threaded opening which is substantially in radial alinement with the ear, and a screw threaded through said 125 opening and having a smooth portion that is guided through the perforation of the aforesaid ear.

5. A device of the character set forth comprising an annulus having an outer peripheral flange which extends at right angles from its body portion, said flange having an opening, a perforated ear which extends from the inner edge of the annulus and is in a plane substantially parallel to the plane of the aforesaid flange, and a set screw which extends through the opening in the flange

and through the perforation of the afore- 10 said ear.

In testimony whereof, I hereunto affix my signature in the presence of two witnesses.

MORTIMER C. ROSENFIELD.
